Primary Examiner — Ricky Pham(57) **CLAIM**

The ornamental design for an ergonomic device for chopsticks, as shown and described.

DESCRIPTION

FIG. 1 is the front view of an ergonomic device for chopsticks showing my new design;
FIG. 2 is 2-2 cross sectional view thereof;
FIG. 3 is left view thereof;
FIG. 4 is 1-1 cross sectional view thereof;
FIG. 5 is the right view thereof;
FIG. 6 is the top view thereof;
FIG. 7 is the bottom view thereof;
FIG. 8 is the back view thereof;
FIG. 9 is the Perspective view showing the front side, the top side, and the right side thereof;
FIG. 10 is the Perspective view showing the back side, the bottom side, and the left side thereof; and,
FIG. 11 is the status of using the ergonomic device for chopsticks.
The chopsticks and hand are shown in broken lines for illustrative purposes only and form no part of the claimed design.
